United States Patent

Des. 235,594
Patented July 1, 1975

235,594

DISPLAY CAROUSEL

Gerald Cohn, New York, N.Y., assignor to Remember
When Sweet Shoppe, Inc., Valley Stream, N.Y.

Filed Apr. 5, 1973, Ser. No. 348,296

Term of patent 14 years

Int Cl. D6—04

U.S. Cl. D6—154

FIG. 1 is a top plan view of a display carousel showing my new design; and

FIG. 2 is a side perspective view, all sides being identical thereto.

I claim:

The ornamental design for a display carousel, as shown and described.
